DISPLAY CARD HOLDER

David Garfinkle, Alameda, Calif.

Application September 14, 1936, Serial No. 100,672

4 Claims. (Cl. 40—152)

The invention relates to a stand or support for displaying price cards and the like.

An object of the invention is to provide a simple device for effectively displaying and supporting price cards and the like, which may be constructed by stamping and forming same out of a single piece of sheet material.

Another object of the invention is to provide a display device with the above mentioned features, which is neat in appearance, presents smooth edges and surfaces, and has all of its parts co-operating to reinforce each other so that the entire device may be made of relatively light gauge sheet metal and still be strong and durable.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

Figure 1 is a perspective view of the display device of my invention viewing same from the front.

Figure 2 is a view similar to Figure 1 but showing same from the rear.

Figure 3 is a side view of the partially completed blank out of which the device is formed.

Figure 4 is an end view of the blank in a more completed form.

Figure 5 is a view similar to Figure 4 showing the device in almost completed form.

In the drawing, which depicts the invention in its preferred form, the device is arranged to be made in one-piece and is desirably formed of sheet metal. One method of forming the device is illustrated, and comprises in general, in cutting or stamping a sheet metal blank 2 such as illustrated in Figure 3, and then by a succession of bending and folding operations made into the completed form shown in Figures 1 and 2.

In its final form, the device desirably comprises angularly related sections generally denoted by the reference numerals 3 and 4 and which may be conveniently termed the card holding section and device supporting section respectively. The supporting section 4 is formed to present a substantially flat base and is so related to the card holding section that when the device is positioned on a table or shelf the card

holding section will be disposed in an upright position.

The section 3 is designed to have removably held thereon suitable cards 6, or the like, on which are printed or otherwise marked prices or desired data. In the present embodiment, arrangement is made for supporting a plurality of tiers of cards on such section, and for so supporting the cards, portions of the section are bent or folded in such manner that without the use of any extraneous or separate pieces, effective card holding and retaining means is provided. The means aforesaid are designed to engage the opposite edges of the cards and are in the nature of transversely extending grooves or channels formed in section 3 at the top and bottom thereof and at some point intermediate such top and bottom. The channel 8 which is at the top of section 3 is formed by merely bending the upper edge portion of the section over but spaced from the front face 5 of the section so as to thus form the channel with the open side lowermost. The channel 9 which is the one located at the bottom of the section, is formed by bending upwardly a portion 12 of the material thereat so as to provide a groove with its open side uppermost. The portion 12 may be considered as part of the integral strip 13 which unites the two sections together, and preferably, such strip 13 is folded over the forward portion of section 4 whereby the section 3 will be more rearwardly disposed and the device will be less apt to tip over at the front.

To provide the intermediate channels on the front side of section 3, a centrally disposed portion of such section is offset outwardly so as to provide a transversely extending rib 14 having its greater thickness at its forward portion whereby opposed grooves 16 and 17 will be defined at the face of the section having their open side respectively at the top and bottom of the rib. It will be clear that with the grooves thus provided, separate sets of cards may be positioned on the device. Thus a set of cards may be held in the upper portion of section 3 by positioning the card edge in the channels or grooves 8 and 16, while one or more cards may be held in the lower portion of the section by positioning the edges of such cards in the channels or grooves 9 and 17. Ordinarily when the device is used as a price indicator, the cards in the lower portion of the section will contain the price, while the upper card or cards will have marked thereon some descriptive matter such as "special", "as advertised", etc. If on the other hand it is desired to hold and display a relatively large card, the latter is

made so as to engage in grooves 8 and 9. It may be incidentally noted that in most instances the cards are made of such size that they will bow outwardly when the opposed edges thereof are 5 operatively disposed in the cooperating grooves. It should also be noted that with the grooves formed in the manner described, no sharp or rough edges will be exposed, and this feature is 10 of importance since frequent handling of the device, particularly for replacing the cards therein, usually occurs.

As a means of bracing the section 3 and at the same time reenforcing the entire device, tongues 21 are struck up from the side edges of the section 4 and made to abut against both the upper and lower portions of the first section. The tongues are preferably secured at their outer extremity to the upper portion of section 3, and desirably such attachment may be effected by 20 spot-welding or the like. It is to be noted that the tongues form with the sections triangular trusses, and this feature coupled with the bracing effect provided by folding and offsetting of the metal to provide the card edge receiving grooves, provides for a very sturdy construction 25 and permits making the device of extremely light gauge sheet material.

For permitting the holder to be readily secured to the goods with which it is being used, so 30 as to prevent accidental misplacement of the holder by the customer, such as when the latter is allowed access to the goods, a lug 22 is struck up from the base and is of such form that when an ordinary can is positioned on end upon the base, 35 the lower seam of the can may be entered between the lug and base and held resiliently gripped thereby. To assist in holding the can and holder more effectively together, an ordinary elastic band is desirably also placed around them.

40 I claim:

1. A display card holder comprising a one-piece sheet metal body having angularly related sections one of which is arranged to provide a base for supporting the other section in an upright position, said second section having vertically spaced substantially coplanar portions united by a transversely extending portion forming with said first portions opposed grooves arranged for the reception of card edges, said upper 45 of said first portions being formed at the upper margin with a transversely extended folded por-

tion providing a card edge receiving groove arranged to cooperate with said one of the grooves aforesaid for retaining a card upon said upper portion, said lower of said first portions being united with said base section by a transversely 5 extending portion forming with said lower portion a groove arranged to cooperate with the other of said opposed grooves for holding a card upon said lower portion, and said base section having stuck up therefrom bracing strips extending 10 to said rear of said first mentioned portions and secured thereat to each of them.

2. A display card holder comprising, a blank of sheet metal provided with a crosswise fold at a mid-portion to define a pair of angularly related 15 portions one adapted to support the other in upright position and extending below and rearwardly from the forward surfaces of said upright portion, said upright portion being set back from the forward portion of said fold and being re-folded 20 thereat vertically to define an upwardly opening transversely extending groove at the base of said upright portion, said upright portion being provided at the upper edge thereof with a forwardly bent portion defining a downwardly opening 25 groove across the top of said portion, said upright portion being provided across an intermediate part thereof with a transverse fold extending forwardly from said portion and being reduced at 30 said portion to define upwardly and downwardly opening grooves incorporated with said above mentioned grooves for receipt of upper and lower edges of supporting cards.

3. A display card holder comprising, a pair of angularly related sides one being adapted for 35 positioning on a shelf or the like to support the other in upright position, card supporting means provided on said upright side, and a member overlying the supporting side and adapted for engagement with the bottom rim of a can to secure 40 the device thereto.

4. A display card holder comprising, a blank of sheet metal formed to provide angularly related sides one being adapted for support on a shelf or the like to hold the other in upright position, 45 card supporting means carried by said upright side, and a projection struck out from said first side and engageable with the rim flange of a can or the like to hold the device thereto.

DAVID GARFINKLE.
